UNITED STATES PATENT OFFICE.

ERNEST H. PASQUÉ, OF DETROIT, MICHIGAN.

MASSAGING DEVICE.

Application filed October 3, 1927. Serial No. 223,796.

This invention relates to massaging devices and has as an object to improve generally devices of this character.

A further object of my invention is to 5 provide means whereby any surface, such as any portion of a patient's body may be simultaneously massaged and treated with a ray of light.

A further object of my invention is to 10 provide an apparatus which may be used to simultaneously massage, heat, and treat with light an affected part.

A further object of my invention is to 15 provide a device which may be used for massaging and melting cosmetic creams into the facial tissues at the same time effecting a valuable tissue stimulating light, heat and massage treatment.

A still further object of my invention is to 20 provide a massaging apparatus having the above mentioned characteristics, which shall be small, compact, and free from dirt collecting crevices or openings. My invention also contemplates the provision of a massaging apparatus which will have no outside 25 mechanical moving parts, which will require no expensive motor, and which while electrically operated will be free of the possibility of electric short circuiting or of shock- 30 ing the user.

Other objects and advantages of my invention will become apparent as the following description proceeds, particularly when reference is had to the accompanying drawings wherein,

Figure 1 is an elevational view of a massaging device constructed in accordance with my invention, and

Figure 2 is a transverse sectional view 40 taken on the line 2-2 of Figure 1.

Referring now particularly to the drawings wherein like reference characters designate corresponding parts throughout all views of the same, the numeral 10 designates 45 generally the actuating mechanism of my massaging device, and the numeral 11 designates generally the movable or the massaging member.

Referring now more particularly to Figure 2 of the drawing, it will be noted that the actuating mechanism 10 includes a casing 12 which I form as a permanent magnet. The casing 12 is provided at one end with a reduced extension 13 slotted as at 14, and is 55 closed at its opposite end by a cap 15 se-

cured to the casing as by screws or other headed fasteners 16.

The reduced extension 13 of the casing 12 is provided with an annular shoulder 17 threaded as at 18 to receive a socket 19 for 60 an incandescent lamp 20. This incandescent lamp is adapted to be illuminated for a purpose which will hereinafter be more fully described.

Mounted within the body of the casing 12 65 is a coil 21 through the center of which there extends a tube 22 which is preferably of steel and which forms a housing for a reciprocable rod 24. The reciprocable rod 24 is provided on one end with a head 25 which is 70 preferably of soft steel and which forms an armature adapted to be moved when the coil 21 is properly energized. For normally urging the head 25 and the rod 24 toward the closed end of the casing 12, I have provided 75 a spring 26 which surrounds the tube 22 and which bears at one end against the head 25 and at its other end against a suitable washer 27 which is arranged adjacent one end of the coil 21. If desired, a second 80 washer 28 similar to the washer 27 may be arranged at the other end of the coil to space the coil from the end of the casing 12. While the tube 22 may be secured within the casing in any desired manner, I prefer 85 to secure the same in place by threading its end as at 29 and projecting this threaded end through the end of the casing 12 where it may be engaged by a suitable nut 30.

I contemplate energizing the coil 21 by 90 an alternating current and for this purpose provide the conductors 31 and 32 adapted to be connected to any suitable source of alternating current. The conductor 31 extends through the casing as at 33 and is then coiled within the casing to form the coil 21 after which it is extended through the opposite end of the casing as at 34 where it is connected as at 35 to one of the terminals of the lamp socket 19. The other terminal 36 of the lamp socket 19 is connected by a wire 37 with one terminal 38 of a switch indicated generally by the reference character 39. The other terminal 40 of the switch 39 is connected to the electric conduit 32. In this manner the lamp socket 19 is wired in series with the coil 21 and when the conductors 31 and 32 are properly connected to a source of alternating current and the switch 39 is moved to bridge the terminals 105 110

38 and 40, current is carried through the coil 21, conductor 34, lamp 19, conductor 37 and switch 39 to the conductor 32. As will be readily understood the flow of an 5 alternating current through the coil 21 causes the armature 25 to be alternately drawn toward the casing 12 and then released from the same, whereupon it will be forced backwardly away from the casing 10 by the spring 26 and the rod 24 will be rapidly reciprocated.

While I have shown the lamp socket as being wired in series with the coil, it is obvious that this socket may readily be wired 15 in parallel with the coil. For example the conductor 34 might be formed as a direct continuation of the conductor 31 and branch conductors then be provided from this conductor to the coil. I therefore desire it to 20 be clearly understood that the lamp socket in my construction may be wired either in series or in parallel with the coil 21.

The movable member 11 of my massaging device includes a tubular member 41 25 slidably mounted on the reduced extension 13 of the casing 12. The free outer end of the tubular member 41 is threaded as at 42 for engagement with a threaded clip 43 which carries a condensing lens 44. In 30 view of the threaded engagement of the clip 43 with the member 42 it is obvious that the clip and the lens may be readily detached from the member 42.

This feature enables the interchangeable 35 use of lenses of various light screening and transmitting properties, such as crystals, quartz or silica glass. Through the use of such lenses the transmitted wave-length of light may be altered at will and as is best 40 suited to the skin under treatment.

For transmitting the reciprocation of the rod 24 to the tubular member 41, I provide the cross bar 45 which is connected as at 46 to the free end of the rod 24. This cross 45 bar projects through the slots 14 in the reduced extension 13 of the casing and is secured by means of screws 47 to the tubular member 41. It will be obvious that reciprocation of the rod 24 will be transmitted 50 through the cross bar 45 to the tubular member 41 and that the rod 24, tubular member 41 and lens 44 will reciprocate as a unit.

In operation the lens 44 constitutes the 55 massaging member. When the switch 39 is closed the coil 21 is energized and the rod 24, tubular member 41 and lens 44 are all reciprocated. The light rays from the incandescent lamp 20 are concentrated by the condensing lens 44 and are projected on the 60 surface or portion of the body which is being massaged by the lens 44.

Further, heat from the incandescent lamp 20 will be transmitted through the lens 44 so that in operation the part being treated 65 will not only be massaged but will also be

treated by heat and light rays having therapeutic effects.

While I have described with some particularity the preferred mechanism which I use for actuating the massaging member, it will be readily understood that various actuating mechanisms may readily be used. It will also be obvious that various changes may be made in the general structure and arrangement of parts which I have described in some detail. It is to be clearly understood therefore that my description is not to be construed as definitive of the limits of my inventive idea and that I reserve the right to make such changes as will fall within the purview of the accompanying claims.

What I claim as my invention is:

1. A massaging device including in combination a lens constituting a massage member, means for vibrating said lens to cause the same to massage a surface, and means for directing rays of light through said lens while the same is in contact with the surface being massaged.

2. A massaging device including in combination a lens constituting a massage member, means for vibrating said lens to cause the same to massage a surface, and a source of light and heat for projecting rays of light and heat through said lens while the same is in contact with the surface being massaged.

3. A massaging device including in combination a lens, the said lens constituting an impact member, means for projecting a ray of light through said lens and means for reciprocating the said lens to cause the same to strike a surface to be massaged.

4. In combination an electro-magnetic vibrating mechanism having a coil and a rod reciprocable within said coil, a massaging member actuated by said rod, and a source of light for projecting a ray of light through said massaging member during actuation of the same by the rod.

5. In a massaging device, a movable member, means for vibrating said member, a lens carried by said movable member and forming an impact surface on the same and a source of light within said movable member for projecting rays of light through said lens.

6. In a massaging device, an electro-magnetic vibrating mechanism, a tubular member connected to said vibrating mechanism for actuation thereby, a lens in one end of said tubular member, the said lens constituting an impact member, and a source of light within the said tubular member.

7. In a massaging device, a casing, a vibrating mechanism within said casing, a lens detachably connected to said casing, said lens constituting a massaging member and being connected to said vibrating mechanism for actuation thereby, and a source of light

carried by said casing for projecting rays of light through said lens.

8. In a massaging device, a casing, an electro-magnetic vibrating mechanism within said casing, a tubular housing carried by said casing, the said tubular housing being connected to the said vibrating mechanism for actuation thereby, a lens carried by the said tubular housing, the said lens constituting a massaging member, and a source of light within the said tubular housing adapted to project rays of light through the said lens.

9. In a massaging device, an elongated tubular casing, a vibrating mechanism within said casing, a lamp socket in one end of said casing, a lamp bulb in said socket, a tubular member sleeved on the said casing, the said tubular member being connected to the said vibrating mechanism for actuation thereby and forming a housing inclosing the said lamp bulb, and a lens arranged in one end of the said tubular member, said

lens constituting a massage member and being adapted to transmit rays of light from said lamp bulb into contact with the surface being massaged.

10. In a massaging device, an elongated tubular casing, an electro-magnetic vibrating mechanism within the said casing, said vibrating mechanism including a coil and a rod reciprocable within the said coil, a lamp socket in one end of the said casing, a lamp bulb in said socket, a tubular member sleeved on the said casing, the said tubular member being connected to the said reciprocable rod for actuation thereby and forming a housing inclosing the said lamp bulb, and a lens carried by one end of the said tubular member, said lens constituting a massage member and being adapted to transmit rays of light from said lamp bulb into contact with the surface being massaged.

In testimony whereof I affix my signature.

ERNEST H. PASQUÉ.
